UNITED STATES PATENT OFFICE.

ELMER E. RIGG, OF COPEVILLE, TEXAS.

DESIGN FOR A BED-SPRING.

SPECIFICATION forming part of Design No. 27,954, dated December 7, 1897.

Application filed July 15, 1897. Serial No. 644,732. Term of patent 3½ years.

To all whom it may concern:

Be it known that I, ELMER E. RIGG, a citizen of the United States, residing at Copeville, in the county of Collin and State of Texas, 5 have invented a new and original Design for a Bed-Spring, of which the following is a specification.

This invention relates to a new and original design for a bed-spring; and it has for its 10 object to provide a design of this character that shall be both useful and ornamental.

The leading feature of the design resides in a pair of twin spirally-coiled bodies having straight horizontal arms extended from 15 their upper coils, beyond one side thereof, and lying in substantially parallel planes, and a bridge-wire connecting the terminals of the straight arms and provided with a series of contiguous V-shaped bends or figures, the 20 central of which bends or figures is of a greater length than the other bends or figures and has its apex extended into the space lying between the coiled bodies, and the other 25 of which bends or figures are disposed in a plane entirely beyond one side of said bodies.

In the drawings, Figure 1 is a perspective

view of a bed-spring embodying the herein-described design. Fig. 2 is a plan view thereof.

Referring to the accompanying drawings, the numerals 1 1 designate a pair of twin 30 spirally-coiled bodies having their upper coils extended into the straight substantially parallel horizontal arms 2. The terminals of the arms 2 beyond the bodies 1 are connected by a bridge-wire 3, lying in the space between 35 the arms 2, and provided with three contiguous V-shaped bends or figures 4. The central bend or figure 4 is of a greater length than the other bends or figures and has its apex 40 disposed in the space between the coiled bodies 1, while the other bends or figures are disposed in planes intersecting said bodies.

What I claim is—

The design for a bed-spring herein shown and described. 45

In testimony that I claim the foregoing as my own I have hereto affixed my signature in the presence of two witnesses.

ELMER E. RIGG.
